UNITED STATES PATENT OFFICE

IVER SYVERSTAD, OF SAN FRANCISCO, CALIFORNIA

POWER MECHANISM

Application filed May 31, 1930. Serial No. 458,650.

This invention relates to improvements in power mechanism and has particular reference to propulsion means for ships.

A further object is to produce a device 5 wherein standard mechanical practises are employed.

A further object is to produce a device which is economical to install.

Other objects and advantages will be apparent during the course of the following 10 description.

In the accompanying drawings forming a part of this specification and in which like numerals are employed to designate like parts 15 throughout the same,

Figure 1 is a side elevation of my device as the same would appear when secured to the vessel,

Figure 2 is a fragmentary detailed cross- 20 sectional view,

Figure 3 is an end elevation of my device as it would appear if it were removed from the vessel, and

Figure 4 is a diagrammatic view illustrating 25 the principle involved.

In ship propulsion the propeller of the ship is acting against a fluid, which fluid being unconfined, tends to dissipate in all directions, and therefore, a large percentage of 30 power delivered by the engines to the propeller is lost.

Applicant has therefore devised a means for retaining this power and again returning the same to the propeller shaft.

35 In the accompanying drawings wherein for the purpose of illustration is shown a preferred embodiment of my invention, the numeral 5 designates a ship having the customary propeller shaft 6 upon which the propeller 7 is keyed. The end of this shaft 6 is reduced in cross-section as shown at 8 and has teeth 9 formed adjacent the end thereof. A casing 11 partly surrounds the path of rotation of the propeller blades and also surrounds the blades 12 of an impeller 13. This impeller wheel is free to rotate upon the reduced portion 8 of the shaft 6. The casing 11 carries spokes 14 which support a ring 16 in which a bearing 17 is mounted. This bearing 40 17 serves to support shafts 18 and 19. These

shafts 18 and 19 carry upon one end large gears as shown at 21 which mesh with the gear teeth 9 and upon their opposite ends they carry gears 22 which mesh with teeth 23 formed upon a reduced portion of the hub of the impeller blades 12. The gear ratio of the gear formed by the teeth 23 to the ratio of the gears 22, is preferably two to one, while the gear ratio between the gears 21 and the gear formed on the end of the shaft 6 is also two to one. As a consequence, the blades 12 may rotate at a speed one-fourth of that of the shaft 6.

The result of this construction is that when the device is secured to a vessel as indicated in Figure 1 and the propeller of the vessel is started, the water being acted upon by the propeller will first move rearwardly as indicated by the arrow A of Figure 4. As soon as it engages the propeller, diagrammatically illustrated at B, the direction of movement of the water will be changed into a spiral movement, as indicated by the spiral continuous arrow C. In this continuous whirling path of water, is placed the impeller D, and it will here be noted that the impeller D is connected back thru suitable gearing designated as a whole by the letter E, to the shaft F. Therefore, applicant has devised a mechanism wherein the whirling action of the water just aft of the propeller, will deliver a portion of its power to an impeller, which impeller will in turn re-transmit this power back to the propeller thru a suitable gearing arrangement. This will of course assist the engines of the vessel and will reduce the amount of power needed, and the consequent saving in fuel and other incidents to operate the vessel.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In a propulsion mechanism, the combination with a propeller, of an impeller having its blades aligned with the axis of rotation of the propeller, said impeller being positioned to the rear of the propeller and in axial alignment therewith and reduction gearing interposed between said propeller and said impeller.
2. In the combination of a driven screw propeller, an impeller positioned in the rear thereof and adjacent thereto and in axial alignment therewith, said impeller having blades so arranged as to form a minimum of resistance to forward or rearward movement of a vessel having the device attached thereto.
3. In the combination of a driven screw propeller, an impeller positioned to the rear of said screw propeller and in axial alignment therewith, the blades of said impeller being in a plane parallel to the axis of rotation to said propeller whereby rotary currents caused by said propeller will be transformed into energy, and gearing interposed between said propeller and said impeller.
4. The combination of a screw propeller, an impeller, a casing surrounding said propeller and impeller, a reduction gearing interposed between said propeller and impeller, said gearing causing said impeller and said propeller to rotate in the same directions and at different speeds with respect to each other.

In testimony whereof I affix my signature.
IVER SYVERSTAD.
